UNITED STATES PATENT OFFICE.

WILLIAM J. NESBITT, OF LOS ANGELES, CALIFORNIA.

HEEL-CUTTING APPARATUS.

1,253,514.

Specification of Letters Patent. Patented Jan. 15, 1918.

Application filed May 7, 1917. Serial No. 167,124.

To all whom it may concern:

Be it known that I, WILLIAM J. NESBITT, a citizen of the United States of America, residing at Los Angeles, county of Los Angeles, State of California, have invented a certain new and useful Heel-Cutting Apparatus; and I do hereby declare the following to be a full, clear, and exact description of the invention, such as will enable others skilled in the art to which it appertains to make and use the same.

This invention relates to improvements in heel cutting apparatus, and it has for one of its objects to provide a novel and improved construction in which both the cutter and the shoe holding device are mounted on a cross arm which is adapted for ready mounting on a supporting pedestal or on the frame which is already in use and carries other devices for operating on shoes in doing repair work.

Another object of the invention is to provide a novel and improved shoe holding device.

Further objects of the invention are to provide a novel and improved heel cutting apparatus which is practical and commercial; simple and compact in construction, easy to operate, convenient and economical to use, and in which the parts and devices are easily adjustable to suit conditions and to make all of the desired straight or angular cuts through the heel.

With the above and other objects in view the invention may be said to consist in the provision of the novel and advantageous features and in the novel and improved construction, arrangement, and combination of parts and devices as will be apparent from the claims and from a careful consideration of the following description of the preferred construction of the improved apparatus, taken in connection with the accompanying drawings in which

Figure 1 is a side elevational view of the improved apparatus disposed on the frame which carries other devices for doing repair work on shoes; Fig. 2 is a side elevational view of the apparatus disposed on a supporting pedestal; Fig. 3 is a broken sectional view taken on the line 3-3 of Fig. 1; Fig. 4 is an enlarged broken sectional view taken on the line 4-4 of Fig. 3; Fig. 5 is an enlarged side elevational view of the apparatus; Fig. 6 is a perspective view of the guide which carries the shoe holding

device; Fig. 7 is a broken plan view of the apparatus; Fig. 8 is a broken sectional view taken on the line 8-8 of Fig. 7; Fig. 9 is a front elevational view showing the apparatus; Fig. 10 is an enlarged broken sectional view taken on the line 10-10 of Fig. 9; Fig. 11 is an enlarged broken sectional view taken on the line 11-11 of Fig. 9; Fig. 12 is a side elevational view of the shoe holding device—the jaws being indicated by dotted lines; and Fig. 13 is an enlarged broken sectional view taken on the line 13-13 of Fig. 12.

Referring to the drawings, the crossarm 15 has adjustably mounted at the ends thereof the mounting 16 for the circular saw 17, and the adjustable mounting 18 for the shoe holding device 19. The crossarm 15 is provided on its underside with the downward extension 20 which is provided with the groove 21 and is adapted to fit in the socket 22.

The mounting 16 consists of the bifurcated bracket 23 which is provided at its upper end with the bearings 24 and is provided at its lower end with the stem 25 which is slidably fitted in the guideway 26 at one end of the crossarm 15. The sprocket wheel 27 is feathered on and operated to drive the shaft 28 which is fitted in the bearings 24 and has one end suitably attached to the circular saw 17. A set screw 29 on the crossarm 15 is adapted to engage the stem 25 to lock the mounting 16 in adjusted position on said crossarm.

The adjustable mounting 18 consists of the stem 30 which has tiltably mounted on its upper end the platform 31 on which is slidably mounted the table 32 on which is pivotally mounted the plate 33 which has thereon the adjustable bar 34 which carries the shoe holding device 19. The platform 31 has one end of its lower bifurcated part mounted on the pivot 35 on the stem 30, and it has the other end provided with the curved slots 36 through which the stem 30 passes the bolt 37 so that the platform can be tilted sidewise of the circular saw 17 and locked in adjusted position. The table 32 is provided on its underside with the dovetail guide 38 which is slidably fitted in a corresponding guideway in the upper part of the platform 31 so that the table 32 can be moved parallel to the circular saw 17. The table 32 has on its flat upper side the pivot 39 to which is connected the plate

33 so that the latter can be turned to turn the bar 34 and consequently the shoe holding device 19 at an angle to the circular saw. The bar 34 is disposed parallel to the circular saw 17 and is provided with a lateral dovetail guide 40 which is fitted in a corresponding guideway in the upper part of the plate 33 so that the bar 34 and consequently the shoe holding device 19 can be moved laterally toward or away from the circular saw 17. The plate 33 has on its rear the extension 41 which has thereon the pivot 42 to which is connected the rear end of the lever 43 which has its forward end provided with the handle 44 and which is provided with a slot 45 through which extends the pivot 46 on the guide 40 so the bar 34 and consequently the shoe holding device can be moved toward or away from the circular saw 17 by swinging the lever 43 to the right or to the left. The lever 43 has thereon the pivot 47 on which is mounted the latch 48 which is pressed by the spring 49 and adapted to engage the teeth 50 on the forward end of the plate 33. The latter can be turned on the pivot 39 by means of the handle 51 which has thereon the pivot 52 on which is mounted the latch 53 which is pressed by the spring 54 and adapted to engage the teeth 55 on the table 32 to lock the plate 33 in adjusted position. The stem 30 is slidably fitted in the guideway 56 which is provided at one end of the crossarm 15, and the latter has thereon the set screw 57 which is adapted to engage the stem 30 to lock the latter in adjusted position.

The shoe holding device 19 consists of the similar jaws 58 which are mounted on the pivot 59 on the depending lug 60 which is provided on the bar 34; said jaws 58 having adjacent edges 61 thereof formed and adapted to fit in the crease between the heel seat and the heel 62 of the shoe 63. The jaws 58 are provided with downwardly converging extensions 64 between which is interposed the roller 65 which is mounted on the pivot 66 on the arm 67 which latter is mounted on the pivot 68 on the lever 69. The latter has a handle 70 at its forward end and has its rear end mounted on the pivot 71 on the lug 72 at the rear end of the bar 34. A spring 73 suitably connected to the bar 34 and bearing against the underside of the lever 69 is adapted to normally hold the lever 69 and consequently the roller 65 in the raised position so that the jaws 58 are normally in the full open position.

On the pivot 74 between the lugs 75 and 75' on the bracket 23 is mounted the lever 76 which is provided at its lower end with the handle 77 and has at its upper end the yoke 78 which is provided with slots 79 into which extend the pins 80 on the ring 81 which is loosely mounted between the col-

lars 82 and 83 on the shaft 28. Instead of effecting movement of the shoe holding device 19 to adjust the heel 62 laterally toward or away from the circular saw 17, the latter when it is found more convenient can be adjusted relatively to the heel 62 by operating the lever 76 to move the shaft 28 and consequently the circular saw 17. The lever 76 has thereon the lugs 84 and 85 on which is slidably mounted the dog 86 which is adapted to engage the teeth 87 on the lug 75 to lock the lever 76 and thus the circular saw 17 in adjusted position. A link 88 is pivotally connected to the dog 86 and the angular operating lever 89 which latter is mounted on the pivot 90 between the lugs 91 and 92 on the lever 76. A spring 93 which bears against the lug 84 and a shoulder 94 on the dog 86 is adapted to normally press the dog 86 into engagement with the teeth 87.

A stop 94 on the platform 31 is adapted to limit the rearward movement of the table 32.

As seen in Figs. 1, 3 and 4, the socket 92 may be suitably attached to the bar 95 on the usual framework 96 which has mounted thereon other devices for doing repair work on shoes; or, as seen in Figs. 2 and 9, said socket 22 may be suitably arranged on the upper part of the supporting pedestal 97. The socket 22 has thereon the set screw 98 which is adapted to extend into the groove 21 to lock the crossarm 15 in adjusted position.

From the foregoing the construction, manner of use, and the advantages of the improved apparatus will be understood by those skilled in the art. It will be seen that the cross arm 15 can be readily mounted on a suitable support or on the framework which carries other devices already in use for doing repair work on shoes. The mounting 16 for the circular saw 17 and also the mounting 18 for the shoe holding device 19 admit of adjustment as may be required to suit conditions in installing and using the apparatus. After placing the heel part of the shoe 63 between the jaws 58 the lever 69 is moved downwardly to cause the roller 65 to move against the extensions 64 to move the edge portions 61 of said jaws into the crease between the heel seat and the heel 62 of the shoe 63 so that the shoe 63 is held clamped by said jaws. To make a straight cut through the heel 62 the lever 43 is operated to move the bar 34 and consequently the shoe holding device 19 at a right angle to the circular saw 17 according to the amount that is desired to cut off of the heel 62, or if found more convenient, the lever 76 is operated to effect movement of the circular saw 17 at a right angle to the shoe holding device according to the amount that it is desired to cut off of the heel. When it

is desired to make an angular cut longitudinally of the heel 62 the heel holding device 19 is turned to the desired angle to the circular saw 17 by the adjustment of the pivot-
5 ed platform 31. When it is desired to make an angular cut transversely through the heel 62, the plate 33 is turned by the handle 51 to have the heel holding device 19 at the de-
sired angle to the circular saw 17. After
10 adjusting the heel holding device 19 or the circular saw 17 according to the cut that is to be made through the heel 62, the table 32 is moved to effect movement of the heel 62 past the circular saw 17 to have the lat-
15 ter cut said heel.

The construction which has been particu-
larly illustrated and described admits of minor changes and modifications—where-
20 fore the right is reserved to all such changes and modifications as do not depart from the spirit and scope of the invention which is defined in the appended claims.

I claim:

1. In heel cutting apparatus, the combi-
25 nation of a socket member, a cross arm pro-
vided with guideways at the end thereof, said crossarm having a part thereon fitted in said socket member, stems fitted in said guideways, a bracket on one of said stems,
30 a platform on the other of said stems, a shaft mounted on said bracket, a circular saw on said shaft, a shoe holding device, and means carried by the platform for adjusting said shoe holding device.

35 2. In heel cutting apparatus, the combi-
nation of a crossarm, stems adjustably mounted on said crossarm, a bracket on one of said stems, a platform on the other of said stems, a circular saw adjustably mount-
40 ed on said bracket, a shoe holding device, and means carried by said platform for adjusting said shoe holding device.

3. In heel cutting apparatus, the combi-
45 nation of a socket member, a crossarm pro-
vided with a part fitted in said socket member, stems adjustably mounted at the ends of said crossarm, a bracket on one of said stems, a platform tiltably mounted on the other of said stems, a shaft mounted on said
50 bracket, a circular saw on said shaft, a shoe holding device, and means carried by said platform for adjusting said shoe holding device.

4. In heel cutting apparatus, the combi-
55 nation of a socket member, a crossarm pro-
vided with guideways at the ends thereof,

said crossarm having a part thereon fitted in said socket member, stems adjustably fitted in said guideways, a bracket on one of said stems, a platform tiltably mounted 60 on the other of said stems, a circular saw adjustably mounted on said bracket, a shoe holding device, and means carried by said platform for adjusting said shoe holding device. 65

5. In shoe heel cutting apparatus, the combination of pivotally mounted jaws hav-
ing adjacent edges thereof formed to fit into the crease between the heel seat and the heel of the shoe, said jaws being pro-
vided with extensions thereon, a pivotally
70 mounted lever, and a roller carried by said lever and adapted to move against said extensions to operate said jaws when the lever is operated. 75

6. In shoe heel cutting apparatus, the combination of pivotally mounted jaws hav-
ing adjacent edges thereof formed to fit into the crease between the heel seat and the heel of the shoe, said jaws having ex-
80 tensions which converge toward the free ends of the extensions, a roller arranged between said extensions, and a pivotally mounted lever operatively connected to said roller. 85

7. In shoe heel cutting apparatus, the combination of pivotally mounted jaws hav-
ing adjacent edges thereof formed to fit into the crease between the heel seat and the heel of the shoe, said jaws being provided 90 with extensions, a pivotally mounted lever, an arm pivotally connected to said lever, and a roller mounted on said arm and adapt-
ed to move against said extensions to operate said jaws when said lever is operated. 95

8. In shoe heel cutting apparatus, the combination of a bar, jaws pivotally mounted on said bar and having adjacent edges thereof formed to fit into the crease between the heel seat and the heel of the shoe, said 100 jaws having extensions which converge to-
ward the free ends of the extensions, a lever pivotally mounted on said bar, an arm pivotally connected to said lever, and a roller mounted on said arm and adapted to move 105 against said extensions to operate said jaws when said lever is operated.

In testimony whereof, I have signed my name to this specification at Los Angeles, county of Los Angeles, State of California, 110 this 27th day of April A. D. 1917.

WILLIAM J. NESBITT.
